(57) **CLAIM**

The ornamental design for a bottle, as shown and described.

DESCRIPTION

FIG. 1 is a top perspective view of a bottle showing my new design;

FIG. 2 is a front elevation view thereof;

FIG. 3 is a rear elevation view thereof;

FIG. 4 is a top plan view thereof; and,

FIG. 5 is a bottom plan view thereof.

The short dash-long dash broken lines in FIGS. 1, 4 & 5 define the bounds of the claim and form no part thereof. The evenly dashed broken lines in FIG. 5 illustrate a portion of the design that forms no part of the claim.
